UNITED STATES PATENT OFFICE.

ARCHIBALD BANNATYNE, OF WATERBURY, CONNECTICUT, ASSIGNOR TO THE BANNATYNE WATCH COMPANY, OF WATERBURY, CONNECTICUT, A CORPORATION OF CONNECTICUT.

WATCH.

1,087,525.

Specification of Letters Patent. Patented Feb. 17, 1914.

Application filed February 7, 1910. Serial No. 542,443.

To all whom it may concern:

Be it known that I, ARCHIBALD BANNATYNE, of the city of Waterbury, county of New Haven, and State of Connecticut, have 5 invented new and useful Improvements in Watches, of which the following is a full, clear, and exact description when taken in connection with the accompanying drawings, which form a part thereof.

10 This invention relates to watches, and more particularly to the stem winding and setting mechanisms.

The invention has for its object the production of simple and efficient stem-winding 15 and setting mechanism, and to this end a rocking bar is constructed so that the wind set pinion is mounted thereon eccentrically between the fulcrum of the bar and the wind wheel and a locking lever is provided 20 which holds the bar in its position for winding under normal conditions.

The invention also relates to the improved construction of the winding stem and crown and the method for connecting the same to 25 the wind set pinion, together with other combinations and improvements hereinafter set forth and claimed.

Referring to the drawings, Figure 1 represents a front view of a portion of the 30 movement of a watch in the watch case embodying the invention, Fig. 2, a similar view of the movement parts alone, Fig. 3, an enlarged detail side view of the cannon pinion and center arbor, Fig. 4, a similar view 35 in vertical section, Fig. 5, a reverse view of the top movement plate, Fig. 6, a similar view with the rocking bar and associated parts shown in different positions, Fig. 7, a front view corresponding to Fig. 2, with 40 the parts shown in the positions corresponding to Fig. 6, Fig. 8, a transverse horizontal section through the rocking bar on line 8-8 of Fig. 5, Fig. 9, a similar view with the locking lever shown in its raised position, 45 some of the parts shown in section, Fig. 10, a detail view of the stem and crown, Fig. 11, a similar view showing the connection between the stem and the stem wind pinion and the locking lever, Fig. 12, a vertical 50 section through the crown and upper end of the stem, Fig. 13, a top view of the upper end of the stem and the inner crown piece,

Fig. 14, a front view of the bridge and stem wind pinion, Fig. 15, a view partly in section showing the connection between the front movement plate and the case of the watch, 55 Fig. 15^A, a horizontal section through one of the pillars supporting the two movement plates, Fig. 16, a top view of a modified form of pillar, and Fig. 17, a side elevation of the 60 same.

In all figures, similar letters of reference represent like parts.

Referring to the drawings, the parts designated by the letter A represent the casing 65 of a watch, which consists of the ordinary ring; B, the front movement plate which is secured to the rear movement plate C by means of pillars D which may be formed with an annular flange F adapted to engage 70 the internal flange G on the casing. In the flange G is located a curved recess H through which the annular flange F may pass when the parts are being assembled, and upon the movement being turned slightly about its 75 center the flange F will engage on the under side of the flange G.

I designates the shaft of the cannon pinion which is provided on its side with more than two internal depressions J, and the 80 upper end of which is closed, as shown at K. When the pinion is fitted over the center arbor L the depressions J will frictionally engage an annular recess M in the center arbor so as to be held thereon, so that it will 85 not be readily removable and will normally rotate with the center arbor L, but owing to the frictional contact it may be rotated independently of the center arbor in setting the hands of the watch. As the shaft of the 90 cannon pinion is provided with a closed end K, it may be forced on the center arbor I, until the upper end of the center arbor contacts with the closed end of the shaft K (Fig. 4). This permits the cannon pinion 95 to receive pressure when the minute hand is forced on the upper end of its shaft without destroying the frictional engagement between the pinion and the arbor.

N represents the winding train and O the 100 setting train.

P designates the wind-set pinion, the shaft Q of which projects through a slot R in the front movement plate B and is connected

or mounted on a rocking bar S pivoted on the inner side of the front movement plate at T. A spring U normally holds the rocking bar in the position shown in Fig. 5, when the arbor or shaft Q of the wind-set wheel P will abut against one end of the slot R, and the wind-set wheel will mesh with the winding train N. The ends of the slot R limit the movement of the wind-set wheel P so that it cannot engage too tightly either the wind train gear N or the set train gear O. When the rocking bar S is moved in the reverse direction against the tension of spring U the wind-set wheel P is moved from the position shown in Figs. 1 and 2, wherein it is engaged with the wind train gear N to the position shown in Fig. 7, wherein it is engaged with the setting train gear O.

Above the wind-set wheel P is a pinion V adapted to be engaged by the stem wind pinion W which is mounted on the stem X of the watch. The stem X is adapted to project through a bridge Y mounted by screws, or other suitable means, on the front of the front plate, and having a depending piece Z adapted to carry the shaft A' of the stem wind pinion W. This stem wind pinion W, as shown more particularly in Fig. 14, is provided with an angular opening B' for the reception of that portion C' of the stem, which is formed angular in cross section. By this engagement the stem wind pinion W is rotated with the stem X.

The inner end of the stem X is provided with a head D' and a reduced portion E' which reduced portion is adapted to fit into a depending, bifurcated piece F' on the locking lever G', so that longitudinal movement of the stem X will rotate the locking lever G' on its pivot H'.

The fulcrum or pivot of the locking lever is shown screw threaded to engage corresponding screw threading in the rear movement plate C, a portion of which is shown in Figs. 5 and 6, so that the locking lever G' is capable of a limited lateral movement when its pivot pin is screwed in or out of the plate C from the position shown in Fig. 8 to that shown in Fig. 9. In the position shown in Fig. 9, the bifurcated portion F' of the locking lever G' is moved laterally away from the head D' of the stem X so that the stem X may be drawn out longitudinally and disengaged from the locking lever G', and the stem wind pinion W. The locking lever G' is provided with a notch I', an inclined face J', a straight edge K', and a finger L'. The rocking bar S is provided with a stud M' adapted normally to rest on the straight edge K' of the locking lever, but if the rocking bar S is moved laterally so that the stud M' comes opposite the inclined face J' and the stem X is moved longitudinally while still engaged with the

locking lever G' the stud M' will travel down the inclined face J' into the notch I' and this movement of the stud M' forces the rocking bar S to the right (Fig. 6) and brings the wind-set pinion P mounted thereon to the left into the position shown in Fig. 7 wherein it engages the set train O.

The finger L' on the locking lever G' prevents a displacement of the locking lever when the stem X is pushed in because it abuts against an upturned shoulder N' on the rocking bar S.

To move the stud M' along the straight edge K' of the locking lever G', it is only necessary to turn the wind wheel V in the reverse direction (see the arrow, Fig. 7) to that in which it ordinarily rotates when winding the watch, because the action of the spring U in holding the wind-set pinion P yieldingly against the coöperating gear of the winding train is overcome by the rotation of the intermeshing pinion V in the direction indicated, thereby shifting the lever G' to a certain extent in a direction away from the winding train. This clears the pinion P from the winding train, with which it is normally engaged, and the stud M' reaches such a position with respect to the edge K' of the locking lever G' that by pulling on the stem X said stud will move along the inclined face J' of the locking lever and into the notch I' of the locking lever, whereby the rocking bar S is laterally shifted and locked in position with the wind-set pinion in mesh with the setting train.

When the wind-set pinion P has completed its oscillatory movement and is engaged with the set train gear O its shaft will contact with the end of the slot R and the rocking bar S will be held from backward movement by the stud M' being engaged in the notch I' of the locking lever G' until the inward longitudinal movement of the stem X forces the stud M' out of the notch I', whereupon the spring U will return the parts to their normal position shown in Figs. 1, 2 and 5.

The right angled piece Z of the bridge Y is provided on its face with a notch O' which is adapted to engage the internal flange G of the casing A and to hold the upper end of the movement in the casing until the stem is forced into place.

The stem X is provided with a crown 120 which is formed of two parts, as shown more particularly in Fig. 12, an outer crown piece P' and an inner crown piece Q'. This inner crown piece Q' is provided with a depending tubular part R' through which 125 projects the upper end of the stem X. The upper end of the stem X is then squared by a tool, as shown in Fig. 13, so that it engages the inner crown piece Q' to rotate therewith. The crown piece Q' is in turn 130

rigidly secured within the outer portion of the crown piece P' so that the stem X is necessarily rotated with the crown piece P'.

In Figs. 16 and 17, a modified form of 5 pillar for the movement plates is shown wherein instead of a flange on the pillar D a lip S' is struck up from the pillar itself which will engage the under side of the flange G of the casing when the parts are 10 assembled in the same way that the flange F of the pillar D does in the form shown in Figs. 1, 15 and 15^A.

It will be understood from the foregoing 15 description that my improved stem winding and setting mechanism is of such simple form that it is particularly well adapted to 20 watches of the cheaper grades. The pinion or wheel W is always in rotative engagement with the stem, irrespective of the longitudinal adjustment of the latter, and this 25 wheel or pinion W is in turn always in operative relation to the wind-set wheel V. The wind-set pinion P, moreover, is so mounted on the rocking bar or yoke S that 30 it is in continual mesh with the wind-set wheel V. By this arrangement, and the provision of the spring, or its equivalent, acting on the rocking bar or yoke, the stem will be simply and quite directly geared 35 with the winding train, under normal conditions, and when it is desired to set the watch, it is merely necessary to pull out the stem so that by the engagement of the inclined surface J' of the member G with 40 the projection M' of the rocking bar or yoke, the latter will be swung on its pivot to carry the wind-set pinion P into mesh with the setting train. The engagement of 45 the wind-set pinion with the setting train M' of the rocking bar, and permit the latter to swing back to its former position 50 under the action of its spring.

The construction of the watch is very 55 much simplified by having the rocking bar or yoke located at the inner side or face of the front movement plate in the manner described and by having the pivot of said rocking bar or yoke eccentrically located with reference to the wheel V and yet approximately in line with the axis of the 60 stem. The wind-set pinion P is effectively limited in its movement by means of the slot R in the front movement plate through which the arbor of said pinion projects. 65 The lever G' lies in a plane parallel to that of the rocking bar or yoke and the stud or pin M' projects perpendicularly from the rocking bar or yoke into coöperation with the edge of the locking lever. I do not limit myself, however, to a construction in

which the pin or stud M' is carried by the rocking bar or yoke, as an obvious reversal of the parts would be within the scope of my invention.

Having now described my invention, 70 what I claim and desire to secure by Letters Patent, is:—

1. In stem winding and setting mechanism for watches, the combination with the front movement plate, of a longitudinally 75 movable rotary stem, a wind-set wheel, means for transmitting rotary movement from said stem to said wind-set wheel in the various lengthwise adjustments of the stem, a winding train on the front or outer face of said movement plate, a setting train on the front or outer face of said movement plate, a wind-set pinion interposed between said trains, a rocking bar located at the inner or rear face of said movement 80 plate and pivoted eccentrically of said wind-set wheel, said wind-set pinion having an arbor secured to the end of said rocking bar and projecting through a slot in said movement plate, and means of connection between said rocking bar and said stem whereby said wind-set pinion is moved laterally from one train to another as said stem is moved lengthwise; substantially as 85 described. 90

2. In stem winding and setting mechanism for watches, the combination with the front movement plate, of a longitudinally 95 movable rotary stem, a wind-set wheel, means for transmitting rotary movement from said stem to said wind-set wheel in the various adjustments of the stem, a winding wheel on the front or outer face of said movement plate, a setting wheel on the front or outer face of said movement plate, 100 a wind-set pinion interposed between said winding wheel and said setting wheel, a rocking bar pivoted to said plate at the inner or rear face thereof approximately in line with said stem and eccentrically of said wind-set wheel, an arbor for said wind-set 105 pinion secured to said rocking bar and extending through a slot in said plate, a spring acting on said rocking bar to hold said wind-set pinion normally in mesh with said winding wheel, and means of connection between said rocking bar and said stem whereby said wind set pinion is carried into 110 mesh with said setting wheel as said stem is pulled outward; substantially as described. 115

3. In stem winding and setting mechanism for watches, the combination with the front movement plate, of a longitudinally 120 movable rotary stem, a wind-set wheel operated thereby, a winding wheel on the front of said movement plate, a setting wheel on the front of said movement plate, a rocking bar at the rear of said movement plate pivoted eccentrically of said wind-set wheel, 125

130

a wind-set pinion interposed between said winding wheel and said setting wheel and having an arbor mounted on the end of said rocking bar and projecting through a slot in said plate, a pivoted operating member connected with the inner end of said stem and lying in a plane parallel to said rocking bar, and a pin or stud extending perpendicularly from one of said last named

parts into coöperating engagement with an inclined edge of the coöperating part; substantially as described.

In witness whereof, I have hereunto set my hand on the 28th day of January, 1910.

ARCHIBALD BANNATYNE.
